UNITED STATES PATENT OFFICE.

EDWARD N. MOOR, OF OAKLAND, CALIFORNIA.

INDEXING AND DIVIDING MACHINE.

1,311,456.

Specification of Letters Patent. Patented July 29, 1919.

Application filed May 29, 1918. Serial No. 237,317.

To all whom it may concern:

Be it known that I, EDWARD N. MOOR, a citizen of the United States, residing at Oakland, in the county of Alameda and State of California, have invented certain new and useful Improvements in Indexing and Dividing Machines, of which the following is a specification.

My invention relates to indexing or dividing machines.

The object is to provide a simple and effective machine for calibrating or dividing work held therein into any desired fractions, either in a vertical or horizontal position, and for drilling holes in the work at any given distance apart upon the radius of any circle.

The stroke of the cutting or marking tool is automatically controlled, to provide for the different lengths of the marks; and feed of the work may be either positive or selective, the latter converting the device into a universal tool for dividing any work held, into any fractional divisions.

My invention consists in the novel machine for the purposes stated, which I shall now fully describe, by reference to the accompanying drawings, in which—

Figure 1 is a front elevation of my machine, in the form adapted for vertical calibration.

Fig. 2 is a top plan view of the same.

Fig. 3 is an end view of the same.

Fig. 4 is a partial vertical section.

Fig. 5 is a front elevation of the machine modified for horizontal calibration of the work held therein.

Fig. 6 is a detail section on the line 6—6 of Fig. 5.

Fig. 7 is a partial detail in front elevation of the machine as modified, for a selective divisional feed of the work.

Fig. 8 is an end view of Fig. 7.

Fig. 9 is a partial detail elevation of the machine modified for divisional drilling.

1 is a bed-plate with standards 2, which carry a cross bar 3, these parts constituting the main frame.

Mounted for rotation in a bearing 1' on the bed-plate is a worm-wheel 4. The worm-wheel carries a chuck 5 to be associated with it in any suitable manner, as, for example, by having a stem 5' dropped into a taper hole in the wheel hub, as seen in Fig. 4. In Fig. 1, is shown in dotted lines, the work 6 to be divided.

7 is a worm-spindle, carrying the worm 8, which engages the worm wheel. One end of the worm-spindle carries a ratchet wheel 9, with which an actuating pawl 10 engages. 60

11 is a swinging pressure arm pivoted in one of the bed-plate standards 2 at 12. This arm carries a short shaft 13, upon which is fixed a ratchet wheel 14. Upon this shaft is also carried in a bearing 13', a presser disk 65 15, the periphery of which is provided with two distance lugs, radially projecting, one designated by 15' being shorter than the other which is designated by 15''.

With the ratchet wheel 14 an actuating 70 pawl 16 engages.

Mounted in one of the standards 2 is the operating or drive shaft 17 with a crank handle 18 on one end. On the drive shaft 75 is a crank disk 19 with a crank pin 20. This pin plays in a slot 21 in the swinging pressure arm 11, and upon said pin, the adjacent ends of both actuating pawls 10 and 16 are pivotally mounted.

A spring 22 connecting the two pawls 80 holds them to their engagement with their respective ratchet wheels.

Mounted for vertical movement in the cross-bar 3 of the main frame is the tool-holder frame 23, controlled by springs 24. 85 The top of this frame carries the contact 25 which is held against the presser disk 15 and its distance lugs 15' and 15''. The foot of the stem 26 of said frame 23 carries the holder 27 for the marking, or other tool 28, 90 as seen in Figs. 3 and 4.

It will now be seen from the foregoing description, reference being had particularly to Figs. 1 to 4, that by the revolution of the crank-handle 18, the pawl 10 effects 95 the movement of the ratchet wheel 9, and through this movement the worm 8 will turn the worm wheel 4 and the work 6. By the same movement of the crank handle the pawl 16 will turn the ratchet wheel 14 and 100 short shaft 13 in order to successively present the plain periphery of the presser disk 15 and its two distance lugs 15' and 15'' to the contact 25; and further by the swinging of the pressure arm 11, due to the crank pin 20, the pressure disk 15 will be forced down on said contact 25, and thereby force down the tool holder frame 23, and cause the marking tool 28 to act upon the work 6. 105

Assume now that in practice, for convenient size the worm wheel 4 has 144 teeth, and that the worm 8 has a duplex thread, 110

as here shown, we then have a ratio of 72 to 1. Then if the ratchet wheel 9 have five teeth, as here shown, it follows that one revolution of the crank 18, will feed the work 5 one degree.

Assume also that the ratchet wheel 14 has ten teeth, and that the distance lugs 15' and 15" are located on the pressure disk 15 oppositely. It will then follow that one revolution of crank 18 will turn the presser disk 15 one tooth, and the downward movement of said disk, due to the depression of the lever 11, will cause the tool 28 to mark the work on the degree to which the latter 10 has been fed. If the presser disk is at the time presenting its plain periphery, the stroke of the tool will be a short one, and this will be the same for four revolutions of the crank. But on the fifth revolution the 15 shorter distance lug 15' will be presented, and the effect will be to increase the length of the tool stroke and the consequent length of the mark it makes on the work. Four succeeding strokes will be short, and for the 20 tenth stroke, the longer distance lug 15" will be presented, and the longest mark will be made on the work. The calibration will thus be the longest mark, followed by four 25 shortest marks, followed by one mark of intervening length, followed by four short marks, followed again by the longest mark, and so on, in the usual form of calibration.

Thus any proper proportioning of these 30 several movements results in dividing the work throughout the circle.

Referring now particularly to Figs. 5 and 6, wherein similar parts are designated by like numerals, I show a modification of the device adapting it for marking the work 35 horizontally instead of vertically.

In this modification the pawl 16 of previous figures is replaced by an eccentric-link 29, fitted on the crank-pin 20, and said link coacts with a vertically swinging link 30 the 40 lower end of which is connected with and reciprocates horizontally the carriage 31 which carries the tool 28. The carriage 31 is fitted upon a vertically adjustable rest 32 carried by the bed plate 1.

50 In order to adapt the machine for selectively dividing the work into any other fractions, I modify it as shown in Figs. 7 and 8. In these figures, enough is shown to indicate the machine in general of the previous 55 figures, many parts being omitted as unnecessary to repeat.

In this modification I mount on the end of the worm-spindle 7, an ordinary dividing plate 33, provided with the usual counting-stops 34. Upon the main frame is adjustably fitted at 35 the index-arm 36, provided with a pin 37 to fit in any of the holes of the annular rows in the dividing plate, said arm having also a handle 38. In this form 60 of the machine, the work is turned to the

desired positions, manually by the operator taking hold of and turning the dividing plate, the degree of this movement being previously determined by fitting the pin of the index arm in the proper hole of the dividing plate, and the counting-stop 34 being previously fixed, with relation to the proper hole. This has the effect of turning the worm spindle 7 and thereby turning the worm wheel 4 and the work it carries, 70 as selectively predetermined. In this operation, the pawl 10 of the general machine is of course inactive, because the ratchet wheel 9 has been removed to give place to the dividing plate assemblage, but the marking device of the general machine is still used as before, by the operation of the crank handle 18.

In Fig. 9 I show the machine as modified for drilling. In this case, the universal dividing plate 33 of Figs. 7 and 8 is used, and the work is turned thereby. Upon one of the standards 2 of the bed plate 1, is adjustably mounted the carrying arm 39 of the drill 40, the latter being pressed down to the 80 work by the lever 41, and rotated by the 90 belt 42, passing over pulleys 43.

I claim:—

1. A machine for the described purpose, comprising a worm-wheel; means for holding the work on said wheel; a worm-spindle engaging said worm-wheel; a reciprocative tool-holder; a tool carried by said holder for acting on the work as turned; a single drive-shaft; and means operated by said 95 shaft for both intermittently turning the worm-spindle and reciprocating the tool-holder in conformity with the intermittent movement of the worm wheel and work.

2. A machine for the described purpose, 105 comprising a worm-wheel; means for holding the work on said wheel; a worm-spindle engaging said worm-wheel; a reciprocative tool-holder; a tool carried by said holder for marking the work; a drive-shaft having a crank; and means operated by said shaft for turning the worm-spindle and reciprocating the tool-holder, comprising a swinging pressure lever in which the crank of said drive shaft is slidably mounted, means 110 coacting with said lever for reciprocating the tool-holder, and connections from said 115 crank to the worm spindle.

3. A machine for the described purpose, 120 comprising a worm-wheel; means for holding the work on said wheel; a worm-spindle engaging said worm-wheel; a reciprocative tool-holder; a tool carried by said holder for marking the work; a drive-shaft having a crank; and means operated by said shaft 125 for turning the worm-spindle and reciprocating the tool-holder, comprising a swinging pressure lever in which the crank of said drive shaft is slidably mounted, an actuating pawl operated by the crank shaft; 130

2. ratchet wheel on the worm-spindle, with which said pawl engages, a second pawl operated by said crank shaft, a second ratchet wheel with which said pawl engages, 5 said ratchet wheel being carried by the pressure lever, and a pressure disk affected by said second ratchet wheel and operating on the tool holder.
4. A machine for the described purpose, 10 comprising a worm-wheel; means for holding the work on said wheel; a worm-spindle engaging said worm-wheel; a reciprocative tool-holder; a tool carried by said holder for marking the work; a drive-shaft having 15 a crank; and means operated by said shaft for turning the worm-spindle and reciprocating the tool-holder, comprising a swinging pressure lever in which the crank of said drive shaft is slidably mounted, an actuating 20 pawl operated by the crank shaft; a ratchet wheel on the worm-spindle, with which said pawl engages, a second pawl operated by said crank shaft, a second ratchet wheel with which said pawl engages, said ratchet 25 wheel being carried by the pressure lever, and a pressure disk affected by said second ratchet wheel, and operating on the tool holder, said pressure disk carrying spaced distance lugs of different lengths to vary 30 the stroke of the tool holder.
5. A machine for the described purpose, comprising a worm-wheel; means for holding the work on said wheel; a worm-spindle engaging said worm-wheel; a reciprocative tool-holder and tool carried thereby for 35 marking the work; means for intermittently turning the worm-spindle; means for reciprocating the tool-holder in conformity with the intermittent movement of the worm wheel and work; and means for automatically varying the stroke of the tool-holder. 40
6. A machine for the described purpose, comprising a worm-wheel; means for holding the work on said wheel; a worm-spindle engaging said worm-wheel; a reciprocative 45 tool-holder and tool carried thereby for marking the work; a drive-shaft; connections from said shaft to turn the worm spindle; connections from said shaft to reciprocate the tool-holder; and means in- 50 cluded in said last named connections for varying the stroke of the tool holder.

In testimony whereof I have signed my name to this specification in the presence of two subscribing witnesses.
